(57) **CLAIM**

We claim the ornamental design for a light emitting diode lamp, as shown and described.

DESCRIPTION

FIG. 1 is a top perspective view of a light emitting diode lamp of the present invention;

FIG. 2 is a front view thereof;

FIG. 3 is a rear view thereof;

FIG. 4 is a first side view thereof;

FIG. 5 is a second side view thereof;

FIG. 6 is a top view thereof;

FIG. 7 is a bottom view thereof; and,

FIG. 8 is a top perspective view thereof shown in an environmental use.

The broken line showing of the base and support structure in FIGS. 1-5 and 7, and the trim in FIG. 8 is included for the purpose of illustrating environmental structures and forms no part of the claimed design.
